UNITED STATES PATENT OFFICE.

JAMES G. FAIRBANKS AND GEORGE L. SAUER, OF MARION, OHIO.

EXCAVATOR.

No. 822,935.

Specification of Letters Patent.

Patented June 12, 1906.

Application filed November 6, 1905. Serial No. 286,081.

To all whom it may concern:

Be it known that we, JAMES G. FAIRBANKS and GEORGE L. SAUER, citizens of the United States, residing at Marion, in the county of Marion and State of Ohio, have invented a new and useful Excavator, of which the following is a specification.

This invention relates to excavators and dredging-machines, and is primarily designed to overcome certain existing disadvantages in dredging and excavating machines of the dipper type now in general use. In this connection it is proposed to mount upon a turn-table all of the machinery necessary for the various operations of dredging or excavating and to so distribute the machinery as to balance the turn-table in all positions thereof.

A further object is to dispense with guys or braces between the derrick and the support upon which the turn-table is mounted, whereby the turn-table is not limited in its rotation and the range of operation of the dipper is materially increased.

Other objects and advantages will appear in the subjoined description; and the invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a side elevation of an excavator embodying the features of the present invention. Fig. 2 is a similar view looking at the end of the support with the turn-table turned to a position at substantially right angles to that shown in Fig. 1. Fig. 3 is a detail fragmentary view showing the arrangement of the thrusting-cable for the dipper-arm. Fig. 4 is an enlarged fragmentary plan view with the derrick-frame broken away.

Like characters of reference designate corresponding parts in all of the figures of the drawings.

The operating parts of the present invention are mounted upon any suitable support—such as a car, a pontoon, or other character of float—as the present apparatus is capable

of being used for dredging as well as for excavating purposes.

In the accompanying drawings the support 1 is in the nature of a pontoon or float having a turn-table 2 mounted upon one end portion thereof and a steam-boiler furnace 3 located at the opposite end of the float, so as to balance the same. The float is of course designed to be anchored in any common or preferred manner—for instance, by means of spuds, one of which has been indicated at 4. The dipper 5 is hinged in any appropriate manner to the lower end of the dipper-arm 6, and the latter works between the sides of a suitable derrick-frame, each side including upwardly-converged beams or bars 7 and 8, rising from the turn-table and projecting beyond the outer edge thereof. A hoisting-cable 9 has one end secured to a block 10, carried by the dipper, from which it leads upwardly and around a pulley 11, carried by the upper portion of the derrick, and thence downwardly around the sheath of the block, thence upwardly around another pulley 12, carried by the derrick, and thence downwardly and rearwardly to a hoisting-drum 13, mounted upon the top of the turn-table adjacent the rear end thereof.

Upon the turn-table there is a suitable engine 14, which is coupled to the drum 13 in any approved manner, and in rear of the drum 13 there is a ballast-box 15, designed to counterbalance the weight of the derrick and the dipper. The engine is provided with a pair of sluing gears 16 and 16', which drive an upright stub-shaft 17, piercing the turn-table and provided upon its lower end with a pinion 18, meshing with a circular rack 19, fixed upon the support 1 concentrically with respect to the axis of the turn-table, whereby the latter may be conveniently rotated to bring the dipper 5 into any desired position. The sluing gears are slidable upon the drive-shaft and are connected by a sleeve *a*, there being a suitable controlling-lever *b* connected to the sleeve for shifting the latter endwise to simultaneously move the sluing gears respectively into and out of engagement with the stub-shaft 17, whereby the turn-table may be rotated in either direction. Steam is conveyed from the steam-boiler through a suitable pipe 20 to the engine, and this supply-pipe communicates with the device 21 for conveying steam and exhaust, which device forms the subject

of United States Patent No. 755,644, issued to us March 29, 1904. The exhaust from the engine is carried by a pipe 22 through the device 21 and into the stack of the steam-boiler furnace. The device 21 is of course located at the axis of the turn-table, so as to permit of the unrestricted rotation of the latter. Upon the top of the circular rack 19 there is a track 23, concentric with the axis of the turn-table and upon which travel rollers 24, carried by the bottom of the turn-table.

For the support of the dipper and its arm there is a cable 25, which has its intermediate portion wound around a drum 26, mounted upon the member 8 of the derrick. One portion of the cable 25 extends from the drum 26 and around a pulley 27, carried by the bar 7 of the derrick, and thence downwardly and connected to the back of the dipper-arm adjacent the lower end thereof, as at 28. The other portion of the cable 25 leads from the drum 26 around a pulley 29, mounted upon the other derrick member 7 and in a reverse direction to the winding of the cable upon the pulley 27. From the pulley 29 the cable leads upwardly and is connected to the top of the dipper-arm, as at 30. As best shown in Fig. 3, it will be seen that the dipper-arm includes two spaced bars or beams, so as to accommodate the hoisting-cable 9, which passes between the members of the dipper-arm. A suitable brake 31 engages the drum 26 and is connected in any suitable manner with a treadle 32, mounted upon the turn-table in position for access by the engineer. When the brake is on, the dipper-arm is held against endwise movement, and when it is desired to move the arm endwise, the brake is released by manipulating the treadle so as to release the drum 26, and thereby permit of the holding-cable 25 running around the drum and the pulleys 27 and 29 to enable the necessary endwise movement of the dipper-arm. It will of course be understood that the dipper-arm is mounted to slide endwise through a guide 33, which is mounted to swing around the common axis of the pulleys 27 and 29, whereby there is no interference with the swinging movement of the dipper-arm by the holding-cable 25.

For backing the dipper there is a cable 34, connected to the back of the lower portion of the dipper-arm and running rearwardly between the guide-pulleys 35, carried by the lower beams 8 of the derrick, said cable running rearwardly to a backing-gear 36, which is driven by the engine. A suitable trip-cable 37 extends between the backing-cable 34 and the bottom of the dipper to open the latter for dumping the dipper.

A suitable shed or canopy 38 is supported by and above the turn-table for the protection of the engineer, and within this shed is mounted a lever 39, connected to the throttle 40 of the engine by a suitable connecting-rod

41. Controlling-levers 42, 43, and 44 are mounted upon the turn-table beneath the shed in convenient reach of the engineer for controlling the hoisting-drum 13, the sluing gear 16, and the backing-drum 36. 70

From the foregoing description it will be noted that with the exception of the steam-boiler furnace all of the necessary machinery is mounted upon the turn-table and there are no guys or braces between the derrick and the support 1, wherefore the turn-table is free to make a complete rotation, which materially increases the effective range of operation of the dipper. Moreover, the several parts of the apparatus are so disposed upon the turn-table as to effectually balance the same, and the float or support is balanced by having the turn-table with the excavating machinery at one end of the support and the steam-boiler furnace at the opposite end thereof. 85

It will here be explained that the drum 26 is positively driven from the shaft of the hoisting-drum 13 in some approved manner—for instance, by-means of a sprocket-chain 45, engaging a sprocket 46 upon the shaft of 90 the hoisting-drum and also engaging a sprocket 47 upon the shaft of the drum 26, there being a suitable reversing-clutch 46 for the sprocket 47 and controlled by a lever 49 for convenience in throwing the drum 26 95 into and out of operation.

In practice the hoisting-cable 9 and the hoisting-drum 13 are employed to swing the dipper-arm outwardly around the axis of the pulleys 27 and 29 as a center when the drum 26 is held against rotation by the brake 31. The drum 26 and the cable 25 are employed to elevate the dipper-arm from the position shown in Fig. 1 to draw the arm rearwardly from the position shown in Fig. 2 and thrust 100 the dipper-arm forwardly from any retracted position when the brake is released from the drum 26 and the cable thereby freed to permit endwise movement of the dipper-arm. In other words, when the brake 31 is applied to the drum 26 the clutch 48 is drawn out of engagement with the drum, whereby the latter is held against rotation and the dipper-arm is held against endwise movement and is permitted to swing around the journals of the 105 pulleys 27 and 29 as a center. By releasing the brake 31 and throwing the clutch 48 into operation the drum 26 may be driven in one direction to thrust the dipper-arm forwardly, or the drum may be driven in the other direction for the purpose of withdrawing the dipper-arm. With the dipper-arm in the position shown in Fig. 2 or in any other extended position it may be drawn back toward the support upon the journals of the pulleys 27 110 and 29 as a center by manipulation of the backing-cable 34 and backing-drum 36. Each of these several operations may be controlled by the respective levers and the treadle 32, mounted upon the turn-table, while the rota- 115 120 125 130

tion of the turn-table is also controlled by one of the levers.

Having thus described the invention, what is claimed is—

- 5 1. In an excavator, the combination with a derrick, of a hoisting-drum, a backing-drum, a thrusting-drum, a swinging and endwise-movable dipper-arm, a hoisting-cable between the dipper-arm and the hoisting-
10 drum, a backing-cable between the backing-drum and the dipper-arm, and thrusting-cables wound in opposite directions around the thrusting-drum and connected to opposite end portions of the dipper-arm.
- 15 2. In an excavator, the combination with a derrick, of a swinging and endwise-movable dipper-arm, a hoisting-drum, a cable between the drum and the dipper-arm, a thrusting-drum, cables extending in opposite directions from the thrusting-drum and connected to opposite end portions of the dipper-arm, an engine coupled to the hoisting-drum, a drive connection between the hoisting-drum and the thrusting-drum, and a clutch for controlling the drive connection of the thrusting-drum.
- 20 3. In an excavator, the combination with a derrick, of a dipper having a dipper-arm, hoisting means for the dipper, a drum independent of the dipper-arm, pulleys carried by the derrick, a cable wound around the drum with its end portions extending therefrom and passing in opposite directions around the respective pulleys, one end of the cable being connected to the lower end portion of the dipper-arm and the other end of the cable being connected to the upper end portion of the dipper-arm, and a brake for the drum.
- 25 4. In an excavator, the combination with a derrick, of a pair of pulleys mounted in
- transverse alinement thereon, a guide journaled in alinement with the axes of the pulleys, a dipper-arm working endwise through the guide and capable of swinging therewith, a drum, a cable wound upon the drum with its end portions extending therefrom and passing in opposite directions around the respective pulleys with the ends of the cable connected to opposite end portions of the dipper-arm, and a brake for the drum. 45
5. In an excavator, the combination with a derrick, of a dipper and its arm, dipper-hoisting means including an engine, pulleys upon the derrick, a drum, cables extending from opposite sides of the drum and running in opposite directions around the respective pulleys, one cable being connected to one end of the dipper-arm and the other cable connected to the other end of said arm, a brake for the drum, and driving mechanism between the engine and the drum and including a reversing-clutch. 50
6. In an excavator, the combination with a derrick, of a dipper and its arm, pulleys upon the derrick, a drum, cables extending from opposite sides of the drum and running in opposite directions around the respective pulleys, one cable being connected to one end of the dipper-arm and the other cable connected to the other end of the arm, an engine, 55 and a drive connection between the engine and the drum including a reversing-clutch. 70

In testimony that we claim the foregoing as our own we have hereto affixed our signatures in the presence of two witnesses.
